UNITED STATES PATENT OFFICE.

JESS L. DEAN, OF DETROIT, MICHIGAN.

SUPPORTING MEANS FOR SLIDING DOORS.

1,161,626.

Specification of Letters Patent. Patented Nov. 23, 1915.

Application filed May 3, 1915. Serial No. 25,371.

To all whom it may concern:

Be it known that I, JESS L. DEAN, a citizen of the United States of America, residing at Detroit, in the county of Wayne and State of Michigan, have invented certain new and useful Improvements in Supporting Means for Sliding Doors, of which the following is a specification, reference being had therein to the accompanying drawings.

10 This invention relates to supporting means for sliding doors and more particularly those of the type that are used on barns and like structures where parts are exposed to the weather, the invention including means whereby the door bearings are housed and whereby the track on which the door runs is so secured as to prevent accidental dislodgment if one of the supporting parts becomes loosened.

20 The invention consists in the matters hereinafter set forth, and more particularly pointed out in the appended claims.

Referring to the drawings, Figure 1 is a view in elevation of a door mounted on supporting means that embody features of the invention; Fig. 2 is a plan view enlarged of a strap, strap hanger and roller; Fig. 3 is a view in detail of the strap hanger and roller; Fig. 4 is a view in section in detail 25 of the strap hanger and roller; Fig. 5 is a transverse section in detail showing the housing of the roller; Figs. 6, 7 and 8 are views in detail of the track rail and bracket for supporting the same; Fig. 9 is a view 30 showing the form of a blank from which the roller housing may be readily formed.

In the drawings, a track rail 1 that preferably has a rounded upper face and at least has a depending longitudinal flange 2 is supported by a series of brackets each having a body 3 with projecting upturned integral flanges 4 and an attaching screw or bolt 5 whereby a bracket may be applied to a wall. A clamping member 6 is oppositely disposed 40 to the flange 4 on the body of the bracket 3, which is notched to overlie, the clamping member and flange 4 coöperating to grip the longitudinal flange of the rail 1. Thus the rail body rests on the integral part 4 of the bracket and is retained there by the clamping member 6, binding screws 7 or the like being used to draw the parts together.

A suitably flanged pulley 18 is journaled on a hollow spindle 8 that operates as a tie 45 to connect the inner wall 9 and the outer wall 10 of a pulley housing. The latter is

formed of a suitable blank such as shown in Fig. 9 folded between its margins whereby an upper or cover wall 11 holds the side walls 9 and 10 in spaced relation, the marginal portions 12 of the wall 10 being inturned and abutting either directly against the inner wall 9 or against a U-shaped hanger 13, the arms of which are not only riveted as indicated at 14 but are also bent 50 to hook over and bear on the top part 11. Preferably the spindle 8 has a cylindrical bore with oil holes 15 whereby the bore may be packed with wicking and lubricant and the end closed in any convenient manner, 55 thus affording constant supply of oil or the like in the pulley hub. Preferably a flange 16 on one end of the member 8 and a cotter pin 17 on the other end effect the locking of the walls 9 and 10 from separating. 75

As a result of this construction a support for a sliding door obtained that provides a very rigid support which is readily applied to a barn or like structure.

The pulley housing is such as to prevent 80 ice and snow from clogging the action of the pulley.

Obviously, changes in the details of construction may be made without departing from the spirit of my invention and I do not 85 care to limit myself to any particular form or arrangement of parts.

What I claim is:—

1. Door supporting means comprising a plurality of track hangers each consisting 90 of a bracket having an outer upturned integral flange, a coöperating clamping member astride the bracket, a rail adapted to be gripped between the flange and clamping member, means for securing the clamping member and flange together, pulley housings each consisting of a single piece of sheet metal bent to form top, side and end walls, a pulley spindle securing the walls of the housing in position, a pulley on the spindle 95 adapted to ride on the rail, and a U strap on each pulley housing for attaching a door thereto.

2. In door supporting means, a sheet metal housing for a pulley comprising a 105 blank bent transversely between its ends to form front, top and back walls, the marginal portions of the back wall being bent forward into contiguity with the margins of the top and front wall, a hollow spindle 110 having an annular flange at one end thereof extending through alined openings in the

front and back wall, a cotter pin securing the spindle in position, an oil duct being provided from the interior of the spindle, a pulley rotatable on the spindle, and a **U** strap having inturned end portions that overlie the top wall of the housings against one side of which the strap is secured.

In testimony whereof I affix my signature in presence of two witnesses.

JESS L. DEAN.
